CLAIM

The ornamental design for a set of knives in a holder having an orange motif, as shown and described.

DESCRIPTION

FIG. 1 is a front, perspective view of the set of knives in a holder having an orange motif in accordance with the present invention, with the rear and side views being mirror images thereof;

FIG. 2 is a bottom plan view of the set of knives in a holder having an orange motif shown in FIG. 1;

FIG. 3 is a top plan view of the set of knives in a holder having an orange motif shown in FIGS. 1-2;

FIG. 4 is a top plan view of one of the knives removed from the set of knives in a holder having an orange motif of FIGS. 1-3; and,

FIG. 5 is a bottom plan view of one of the knives removed from the set of knives in a holder having an orange motif of FIGS. 1-4.

The knife shown in FIGS. 4 and 5 is shown separately for ease of illustration.
